CLAIM

The ornamental design for an electronic display overlay attachment as shown and described.

DESCRIPTION

FIG. 1 is a front perspective view of an electronic display overlay attachment;

FIG. 2 is a front elevation view thereof;

FIG. 3 is rear elevation view thereof;

FIG. 4 is a top plan view thereof;

FIG. 5 is a bottom plan view thereof;

FIG. 6 is a left side elevation view thereof;

FIG. 7 is a right side elevation view thereof; and,

FIG. 8 is a front perspective view thereof, shown in an environment of use.

The broken lines in FIGS. 2–7 illustrate portions of the electronic display overlay attachment that form no part of the claimed design. The broken lines in FIG. 8 representing the electronic display and another electronic display overlay attachment are environment and form no part of the claimed design.
